UNITED STATES PATENT OFFICE

104,065

DESIGN FOR A HANDLE FOR KITCHEN UTENSILS OR SIMILAR ARTICLES

Clarence R. T. Hess, Prairie View, Ill., assignor to Edward Katzinger Company, Chicago, Ill., a corporation of Illinois

Application January 22, 1937, Serial No. 67,222

Term of patent 14 years

To all whom it may concern:

Be it known that I, Clarence R. T. Hess, a citizen of the United States, residing at Prairie View, in the county of Lake and State of Illinois, have invented a new, original, and ornamental Design for a Handle for Kitchen Utensils or Similar Articles, of which the following is a specification, reference being had to the accompanying drawing, forming part thereof.

Fig. 1 is a plan view of a handle showing the present design;

Fig. 2 is a side elevational view thereof;

Fig. 3 is an end elevational view taken at the ferrule end of the handle.

I claim:

The ornamental design for a handle for kitchen utensils or similar articles, as shown.

CLARENCE R. T. HESS.
